B. I. DOWNING

LANTERN

Filed Oct. 11, 1927

INVENTOR.
BARRY I. DOWNING
BY *Danny G. Schroeder*
ATTORNEY.

UNITED STATES PATENT OFFICE.

BARRY I. DOWNING, OF PITTSBURG, CALIFORNIA.

LANTERN.

Application filed October 11, 1927. Serial No. 225,454.

The invention forming the subject matter of this application relates to safety lanterns of the type in which the lamp always assumes an upright position, regardless of the 5 position of the lantern.

The principal object of the invention is to provide a safety lantern to be used on construction work or the like as a signal, in which lantern the lamp is mounted upon a 10 weighted ring in such a manner as to keep the light or the lamp in an upright position regardless of the position of the lantern.

Another object of the invention is to provide a lantern in which an oil lamp is caused 15 to rotate in such a manner as to obviate any danger of the spilling of the oil therefrom in any position of the lantern support or lantern housing.

A further object of this invention is to 20 provide a safety lantern in which the lamp is supported in such a way that the weight of the lamp turns the same in upright position and in which a weighted ring is adapted to support the lamp so as to turn the pivot 25 of said lamp in parallelism with the direction of the tilting of the lantern housing.

With the above and other objects in view, my invention resides in the combination and arrangement of parts and in the details 30 of construction hereinafter described and claimed, it being understood that changes in the precise embodiment of the invention hereinafter disclosed may be made within the scope of the appended claims without departing from the spirit of the invention. The essential features of the invention involved in the carrying out of the objects indicated are fully illustrated in the accompanying drawings, in which—

40 Figure 1 is a sectional view of the safety lantern;

Figure 2 is a sectional view taken along the line 2—2 of Figure 1; and

45 Figure 3 is a fragmentary detail of the safety lantern base locking means.

The safety lanterns in use at present on the highways or on construction work are very frequently disturbed in their position by passing vehicles or for some other reason.

50 There are some safety lanterns on the market in which the lamp may be rotated in a direction, thereby preventing the spilling of the oil and holding the lantern in an upright position when the lantern is tilted at right angles to the supporting plane of the

lamp. The tilting of these lanterns in a parallel plane with the supporting plane of the lamp will cause the oil to leak and to drown out the light. In my lantern, the lamp or the light is held in a true perpendicular position regardless of the angle and direction of the lantern tilting.

In carrying out my invention, I provide a housing denoted by the numeral 1. The housing 1 is preferably dome-like in shape and has apertures 2 at the top thereof for the egress of gases produced by a burning lamp 3 inside of the dome-like housing 1. Windows 4 covered by colored (preferably red) glass 5 are provided for permitting the 70 light rays of the lamp 3 to be visible outside of the dome-like housing 1.

A base 6 is supported at the bottom of the dome-like housing 1 on lugs 7. Openings 8 are cut into the periphery of the base plate 6. Said openings are so arranged that the base 6 may be readily detached and removed from the housing 1 by aligning the openings 8 with the lugs 7, thereby permitting the passing of said base over the lug 7. It is apparent that after the base 6 is placed into the bottom of the dome-like housing 1, the whole base may be turned so as to bring the openings 8 out of alignment with the lugs 7, thus supporting said base on said lugs.

An annular flange 9 extends upwardly from the base 6, and it is sufficiently deep to receive therein the lamp 3. Guides 10 are oppositely disposed on the free end of the annular flange 9. A ring 11 is slidable in said guides 10. A weight 12 is disposed on one side of the ring 11 as it is clearly shown in Figure 2. The weight is cut in as at 13 adjacent to the ring 11 in order to permit the same to pass over the guides 10. The extent of the cutout portion 13 is shown in dotted lines in Figure 2. Bearings 14 extend upwardly and oppositely from the inside periphery of the ring 11. The bearings are made of a spring clip in order to facilitate the ready removal of the lamp from the supporting means. Pivots 15 extend from the lamp 3 and are rotatably secured in the spring clip bearings 14. As it is clearly shown in Figure 1, the pivots 15 are so disposed on the lamp that the oil container of said lamp falls below the supporting line, thereby counterbalancing the same.

The functions of the supporting means

are readily understood from the aforesaid description. The dome-shaped housing 1 is made narrower on the top than on the bottom thereof, so as to make it more difficult 5 to be thrown out of the upright position by the wind or by any other temporary force. The center of the gravity of the lamp 3 is below the pivots 15. Thus, the lamp is always turned so that the center of gravity 10 thereof takes up the position below the pivots 15, thereby holding the lamp in upright position. In the event the safety lantern is tilted in a direction parallel with the axis of the pivot 15, the weight 12 tends to assume the lowest possible position, thus forcing 15 the ring 11 to slide in the guides 10 and rotate around the center, thereby bringing the pivot 15 in such a position as to permit the rotation of the lamp 3 therein by the 20 counterbalance thereof. Thus the bearings 14 are always brought into a position in which the axis of the pivot 15 is at right angles to the direction of the tilting of the safety lantern, regardless in which direction 25 the lantern is tilted.

A hook 16 is secured to the top of the dome-like housing 1. A chain or any other support 17 is secured therein by which hook or chain 17 the lantern is suspended in 30 any desirable position.

It will be recognized that a particularly simple device is provided to hold the lamp always in an upright position and which device combines light weight and sensitivity 35 of movement with a ruggedness of construction and positiveness of operation, especially adapting the safety lantern for its use. The device requires no careful setting up, and lends itself to effective application by the 40 labor ordinarily available.

Having thus described my invention, what I now claim as novel and desire to secure by Letters Patent is:

1. A safety lantern comprising a housing, 45 a ring, means to slidably support the periphery of said ring, a weight eccentrically disposed on said ring for rotating the same, and a lamp pivoted on said ring so as to be held in an upright position.
2. A safety lantern comprising a housing, 50 a ring, brackets on said housing for slidably supporting the periphery of said ring, a

weight eccentrically disposed on said ring, and a lamp pivoted on said ring so as to be held in an upright position. 55

3. A safety lantern comprising a housing, a removable bottom in the housing, an annular flange extending from said bottom, a ring, guides on said flange for slidably supporting said ring, a weight eccentrically disposed on said ring, and a lamp pivoted on said ring so as to be held in an upright position. 60

4. A safety lantern comprising a dome like housing, having windows thereon, a base 65 in said housing, a ring, guides on said base for slidably supporting the outside periphery of said ring, a weight disposed on one side of the ring and adapted to clear said guides, bearings on the inside periphery 70 of said ring, and a lamp pivotally supported in said bearings.

5. A safety lantern comprising a dome like housing, having windows thereon, a removable base in said housing, an annular flange 75 extending from said base, guides on said flange, a ring, the outside periphery thereof being slidably supported between said guides, a weight disposed on one side of the 80 ring, bearings on the inside periphery of said ring, and a lamp pivotally supported in said bearings.

6. A safety lantern comprising a dome shaped housing, said housing being narrower at the top than at the bottom thereof, a 85 lamp in the housing, means for rotatably and slidably supporting said lamp so as to hold the same in an upright position.

7. A safety lantern comprising a supporting member, having guides therein; an eccentrically weighted annular element supported in the guides and being rotatable 90 therein in the plane of the guides by the action of the eccentric weight thereof; and a lighting element pivotally supported on 95 said weighted element, the center of gravity of said lighting element being below the pivotal point thereof; said lighting element being rotatable in said weighted element around an axis of rotation at right angles 100 to the axis of rotation of said weighted element.

In testimony whereof I affix my signature.
BARRY I. DOWNING.
